U.S. Appl. No. 29/763,128, filed Dec. 21, 2020, Brunner.

Primary Examiner — Ricky Pham

(74) Attorney, Agent, or Firm — Crowell & Moring LLP

(57) **CLAIM**

The ornamental design for a knife, as shown and described.

DESCRIPTION

FIG. 1 is a perspective view of a knife showing the new design;

FIG. 2 is a right side view thereof;

FIG. 3 is a left side view thereof;

FIG. 4 is a top view thereof;

FIG. 5 is a bottom view thereof;

FIG. 6 is a front view thereof; and,

FIG. 7 is a rear view thereof.

The broken lines are for environmental purposes only and do not form any part of the claimed design.

1 Claim, 3 Drawing Sheets---
